US00D602019S

(12) **United States Design Patent**
Wang et al.

(10) **Patent No.:** US D602,019 S
(45) **Date of Patent:** ** Oct. 13, 2009

(54) **NETWORK STORAGE DEVICE**

(75) Inventors: **Qian Wang**, Shenzhen (CN);
Tzu-Cheng Yu, Taipei Hsien (TW)

(73) Assignee: **FIH (Hong Kong) Limited**, Kowloon
(HK)

(**) Term: **14 Years**

(21) Appl. No.: **29/298,014**

(22) Filed: **Nov. 27, 2007**

(30) **Foreign Application Priority Data**

Oct. 23, 2007 (CN) 2007 3 0201864

(51) **LOC (9) Cl.** 14-02

(52) **U.S. Cl.** D14/356

(58) **Field of Classification Search** D14/137,

(57) **CLAIM**

The ornamental design for a network storage device, as shown and described.

DESCRIPTION

FIG. 1 is a perspective view of a network storage device showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines showing of the unclaimed portions in FIGS. 3 and 7 form no part of the claimed design.

1 Claim, 7 Drawing Sheets
